UNITED STATES PATENT OFFICE.

EMILE MARZOLI, OF RENENS, SWITZERLAND.

REINFORCED-CONCRETE POLE.

1,372,362.

Specification of Letters Patent. Patented Mar. 22, 1921.

Application filed June 18, 1920. Serial No. 389,926.

To all whom it may concern:

Be it known that I, EMILE MARZOLI, master builder, a subject of the King of Italy, residing at Renens, Canton of Vaud, in the 5 Confederation of Switzerland, have invented certain new and useful Improvements in Reinforced-Concrete Poles, of which the following is a specification.

The present invention relates to a reinforced concrete pole having a star shaped cross section with at least three points, at least one iron bar placed axially in the center of the star and at least one iron bar arranged near to the end of each point of the 15 star.

The annexed drawing shows by way of example several embodiments of the invention.

Figure 1 is an elevation showing a pole 20 for supporting an aerial line of electric traction.

Fig. 2 is an elevation showing a pole for supporting telegraph and telephone lines;

Figs. 3 and 4 are elevations on an enlarged 25 scale of a portion of the reinforcement of the poles represented in Figs. 1 and 2.

Figs. 5 and 6 are cross sections on an enlarged scale of two embodiments of the invention.

Fig. 7 is a perspective view of a portion 30 of a mold which may be employed for making the pole.

Fig. 8 is an elevation showing a strengthened reinforcement of a pole;

Fig. 9 is a side view of a portion of the 35 pole;

Fig. 10 is a cross sectional view of Fig. 8 and

Fig. 11 is a cross section of another form 40 of the pole.

The pole *a* shown in Fig. 1 is solid throughout, is of monolithic construction and has a cross section as shown in Fig. 5, and it is provided at intervals with circular 45 transverse ribs *b*. The body of the pole *a* comprises an iron bar *c* forming an axial reinforcement and iron bars *d* which are placed near the ends of the points of the star formed by the cross section of the said body.

Light reinforcements *e* connect the bars *c* and *d* and form diagonal reinforcements arranged as shown in Figs. 3 and 4. *h* are transverse reinforcements which may be more or less distant from each other.

The ribs *b* may be employed for fixing a support *f* for an aerial line for electric trac-

tion, as shown in Fig. 1. They may also carry a support *g* for telephone or telegraph lines as shown in Fig. 2; said supports *f*, *g*, comprising iron rings *f'*, *g'*, respectively, 60 which encircle the said ribs *b*.

The molding of the pole may be made for instance by means of a mold such as shown in Fig. 7.

In this figure the left portion shows the 65 section of the mold at one of the ribs *b* and the right portion the section of the mold between two ribs *b*.

The transverse ribs may have another shape than an annular one, for instance as 70 shown on Fig. 6.

The pole may be made without transverse ribs.

The concrete employed for the manufacture of this pole may be made either with a 75 mixture of cement and sand or with a mixture of cement and slags or any other material which may be allied to the cement.

The pole *a* shown in Figs. 8 to 11 is provided with annular ribs *b*. Its body comprises an iron bar *c* forming an axial reinforcement and iron bar *d* arranged near the ends of the points of the star formed by the cross section of the said body. The light reinforcements *e* connect the irons *c* and *d* 85 together and form diagonal reinforcements disposed as shown in Fig. 8. The iron bars *d* are provided on a portion of their length with strengthening irons *d'*, which are bent around the said bars *d* as shown in Fig. 7 90 and form a loop *d''* surrounding the axial iron bar, *c*.

These reinforcements impart great resisting power to the metal frame-work of the pole for that portion of its length which is 95 the most exposed to bending strains without giving to the iron bars *d* throughout their entire length a section equal to the sum of the sections of *d* and *d'*.

What I claim is:—

1. A solid concrete pole of substantially 100 star-shaped section and of monolithic construction, formed at intervals with integral horizontal ribs connecting together the successive arms of the star; said pole having 105 embedded in it a metal reinforcing framework comprising an axially-arranged vertical bar and at least one vertical bar arranged adjacent the extremity of each of said star arms, all of said bars extending from end to 110 end of the pole, horizontal reinforcements connecting the axial bar with the several

second-named bars, and diagonal reinforcements also connecting said axial bar with said second-named bars.

2. A reinforced concrete pole of substantially star-shaped section, formed at intervals with integral horizontal ribs connecting together the successive arms of the star; said pole having embedded in it a metal framework comprising an axially-arranged vertical bar, a vertical bar arranged adjacent the extremity of each of said star arms, all of said bars extending from end to end

of the pole, and a strengthening bar extending alongside each last-named vertical bar for a portion of its length but structurally 15 separate therefrom, said strengthening bars being bent around said last-named vertical bars and looped around the axial bar.

In testimony whereof I affix my signature in presence of two witnesses.

EMILE MARZOLI.

Witnesses:

W. TMER,
THEODORE TMER.
